UNITED STATES PATENT OFFICE.

GEORGE H. HURD, OF GEORGETOWN, MASSACHUSETTS, ASSIGNOR TO UNITED SHOE MACHINERY CORPORATION, OF PATERSON, NEW JERSEY, A CORPORATION OF NEW JERSEY.

SEWING-MACHINE.

1,393,783.

Specification of Letters Patent.

Patented Oct. 18, 1921.

Application filed September 17, 1918. Serial No. 254,476.

To all whom it may concern:

Be it known that I, GEORGE H. HURD, a citizen of the United States, residing at Georgetown, in the county of Essex and State 5 of Massachusetts, have invented certain new and useful Improvements in Sewing-Machines; and I do hereby declare the following to be a full, clear, and exact description of the invention, such as will enable others 10 skilled in the art to which it appertains to make and use the same.

This invention relates to sewing machines for sewing outsoles to the uppers of shoes and more particularly to a presser-foot for 15 use on such machines.

The object of the invention is to provide a presser-foot for shoe sewing machines of the above class having a novel and improved construction for lifting and turning back 20 the channel flap of an outsole and holding the same out of the path of the needle and awl.

With the above object in view the invention consists in the novel and improved constructions, arrangements and combinations 25 of parts hereinafter described and particularly pointed out in the claims, the advantages of which will be readily appreciated by those skilled in the art.

The invention will be readily understood 30 from the accompanying drawings illustrating the invention in its preferred form, and the following detailed description of the constructions therein shown.

In the drawings Figure 1 is a perspective 35 view of a portion of a shoe sewing machine having the invention applied thereto; Fig. 2 is a view in front elevation of the presser-foot shown in Fig. 1 detached from the machine; and Fig. 3 is a view of the presser-foot taken in the direction of the arrow, 40 Fig. 2.

The shoe sewing machine illustrated in the drawing is a machine of the so-called McKay type, an example of which is illustrated 45 in the patent to McKay and Mathies, No. 36,163, dated August 12, 1862, and comprises a vertically reciprocating straight hook needle 2, and a rotatable horn 4 adapted to enter the shoe and support the sole of the shoe upon its upper end or tip, a work-feeding awl 6, and a presser-foot 8. The presser-foot is mounted upon a carrier 10 and, as is usual in this type of machine, is 50 located substantially in the vertical plane of

the line of feed of the machine, and is directed forwardly from the carrier 10 at an acute angle to the plane of the sole of a shoe placed on the horn.

The presser-foot of the machine illustrated 60 in the drawing is especially constructed for operating upon shoes the outsoles of which have the usual marginal flap or lip made by the diagonal cut or channel extending from the marginal portion of the sole toward the 65 central portion thereof. It is the usual practice in the manufacture of shoes to turn back the channel flap of the outsole and set the same in position before the outsole is applied to the shoe. When this practice is followed 70 it is necessary after the outsole is stitched to the shoe bottom to turn the channel flap from the position in which it is set back against the body of the outsole and cement the same in position, this latter operation being known as the "channel laying" 75 operation. These operations require the expenditure of considerable labor and time and the exercise of some degree of skill, and it is obviously of considerable advantage to 80 illustrate these operations or certain parts thereof. To this end the presser-foot of the present machine is provided with devices having a novel and improved construction and mode of operation, by which during the 85 sewing operation the channel flap is lifted from the body of the outsole and turned back to expose the line along which the seam is to be sewn, and is held in back-turned position out of the paths of the needle and awl. 90

In sewing outsoles having channel flaps formed in the usual manner, as above described, upon machines of the McKay type, the lower end of the presser-foot engages the marginal portion of the sole outside of the 95 channel flap close to the base of the flap, and through its contact with the base of the flap forms a guide for the shoe. In order to lift the channel flap of the outsole as the shoe is advanced across the tip of the horn, 100 the presser-foot of the machine illustrated in the drawing is provided with a rigid plate-like projection or plow 12 mounted on the presser-foot at the base thereof, and extending from the rear side of the presser-foot, or 105 the side away from the operator, in a general direction reverse to the direction of feed of the machine. This projection is arranged so that its lower edge extends from the presser-foot close to the base of the channel flap, 110

and is tapered from its base toward its outer end so that it will engage beneath the partially down-turned flap and lift the same away from the body of the outsole. As 5 illustrated clearly in Fig. 3 of the drawings, the outer end portion of the plow 12 which first engages the flap is deflected or bent forwardly in a curve, the extent of the deflection thereof increasing from the lower to the 10 upper edge of the plow. The curvature of the flap-engaging face of the plow thus conforms substantially with the curvature of the portion of the flap engaged thereby as the flap is lifted and turned back by the 15 plow. With this construction, the outer end of the plow engages beneath the partially down-turned flap and lifts the same away from the marginal portion of the outsole and the inner part of the plow adjacent the body 20 of the presser-foot, and turns the lip back substantially into an upright position. On account of the curvature of the lip-engaging face of the plow, the lip is lifted and turned back gradually and easily without exerting 25 any appreciable frictional resistance to the movement of the shoe, and there is no tendency for the plow to catch in and tear or otherwise injure the stock.

In order to hold the channel flap of the 30 outsole out of the paths of the needle and awl after the lip has advanced beyond the body of the pressure-foot, the presser-foot is formed with a second rigid plate-like projection or wing 14 mounted on the presser- 35 foot adjacent its base and extending from the rear side of the presser-foot in an oblique direction upwardly and in the direction of feed beyond the awl and the path of the reciprocating needle. As clearly shown in Fig. 40 3, the projection 14 is curved to a slight degree, its outer end being directed slightly to the rear so as to hold the outer portion of the lip well out of the path of the needle. It is found to be sufficiently effective to construct 45 the projection 14 so that it engages the outer or upper portion of the lip only inasmuch as the lower portion of the lip is held back by its engagement with the base of the presser-foot.

50 The projections 12 and 14 are preferably formed integral with the presser-foot as illustrated in the drawings, although they may be formed separately therefrom, and rigidly secured to the presser-foot in any 55 suitable or convenient manner.

Having explained the nature and object of the invention, and having specifically described a preferred embodiment of the invention, what is claimed is:

60 1. A sewing machine for sewing outsoles to the uppers of shoes, having, in combination, stitch forming devices including a hook needle, a work support and a presser foot, comprising a rigid body extending obliquely 65 downward and in the direction of feed and

terminating at its lower end in a work engaging foot, a rigid plow mounted on the body of the presser-foot at its base and directed in a direction reverse to the direction of feed for lifting and turning back the 70 channel flap, and a rigid plate-like projection mounted on the body of the presser-foot adjacent its base and extending from the body of the presser-foot in the direction of feed for engaging the outer portion of 75 the channel flap and holding the same out of the paths of the needle and awl.

2. A sewing machine for sewing outsoles to the uppers of shoes, having, in combination, stitch forming devices including a 80 straight hook needle, a work support and a presser-foot having a rigid plow point mounted on the body of the presser-foot at its base and directed in a direction reverse to the direction of feed so that it will extend along the bottom of a channel beneath the partially down-turned channel flap and lift the same from the body of the outsole, and a rigid wing mounted on the body of the presser-foot adjacent its base and extending from the body of the presser-foot obliquely upward and in the direction of feed for engaging the outer portion of the 85 channel flap and holding the same out of the paths of the needle and awl. 90

3. A sewing machine for sewing outsoles to the uppers of shoes, having, in combination, stitch forming devices including a straight hook needle, a work support and a presser-foot having a rigid plow mounted 100 on and extending from the base of the body of the presser-foot in a direction reverse to the direction of feed for engaging beneath the partially down-turned channel flap, and having a flap-engaging face curved to conform to the curvature of the portion of the flap engaged thereby, and a rigid wing extending from the body of the presser-foot 105 in the direction of feed for holding the channel flap out of the paths of the needle and awl. 110

4. A machine for sewing outsoles to the uppers of shoes, having, in combination, stitch forming devices including a straight hook needle, a work support and a presser-foot, comprising a rigid body extending obliquely downward and in the direction of feed and terminating at its lower end in a work engaging foot, a rigid plow mounted on the body of the presser-foot at 115 its base and directed in a direction reverse to the direction of feed for lifting and turning back the channel flap, and a rigid plate-like wing mounted on the body of the presser-foot adjacent its base, and having its outer portion deflected rearwardly in a curve for engaging the outer portion of the channel flap to hold the same out of the paths of the needle and awl. 120
